UNITED STATES PATENT OFFICE.

LOUIS HAMMER, OF OLDS, ALBERTA, CANADA, ASSIGNOR, BY DIRECT AND MESNE ASSIGNMENTS, OF ONE-EIGHTH TO ABSALOM CLARK BURY AND ONE-EIGHTH TO FRANK L. LANDON, BOTH OF OLDS, ALBERTA, CANADA.

AUTO PULL-OUT.

1,256,791.

Specification of Letters Patent. Patented Feb. 19, 1918.

Application filed October 8, 1917. Serial No. 194,564.

To all whom it may concern:

Be it known that I, LOUIS HAMMER, residing at Olds, in the Province of Alberta, Dominion of Canada, have invented a new and Improved Auto Pull-Out, of which the following is a specification.

My invention has for its object to provide a simple and inexpensive attachment for motor vehicles that can be conveniently applied to any of the ordinary types of motor vehicle frames and which may be quickly adjusted for utilizing the motor power for pulling the vehicle out of ruts, mud holes, etc.

Another object of my invention is to provide an attachment for the purpose stated adapted for being compactly mounted on the vehicle chassis, at the front end thereof, and having a driving member arranged for being quickly coupled with the engine shaft when the attachment is to be used for pulling the vehicle out and which is as readily disconnected from the engine shaft after having exerted its function.

With other objects in view, that will hereinafter appear, my invention resides in an attachment of the character stated, that embodies the peculiar construction and novel arrangement of parts, all of which will be hereinafter fully described, specifically pointed out in the appended claims and illustrated in the accompanying drawings, in which:

Figure 1 is a perspective view of my invention, the same being shown in the operative position on a motor vehicle.

Fig. 2 is a front view of the attachment.

Fig. 3 is a plan view thereof as applied to the vehicle framing.

Fig. 4 is a perspective view of the winding drums and the worm or power transmitting shaft, separated.

Fig. 5 is a detail cross section of my pull-out device on the line 5—5 of Fig. 2.

Fig. 6 is a similar view taken on the line 6—6 on Fig. 2.

In the practical arrangement, my "pull-out attachment" comprises essentially a pair of end brackets 1—1 shaped for being suitably bolted to the steel bars or frame members 2, as is best shown in Figs. 2 and 3, by reference to which it will be noticed a power shaft 4 journals at its ends in the said brackets 1—1.

One or more, two being shown, cable 55 winding drums 5—5 are keyed onto the shaft 4 and midway, between the two drums, a worm wheel 6 is mounted to turn with the said shaft.

Cooperative with the worm wheel 6 is a 60 worm screw 70 that forms a fixed part of a power transmitting shaft 7 that journals in bearing boxes 80—80 on a two-part boxing 8, secured by bolts 9—9, to the top or cross members 2—2 of the front frame members, as 65 shown.

Shaft 7 has a clutch end 71 and the said shaft is endwise slidable, with respect to its journal bearings and the worm screw, to adapt it for being readily shifted into a 70 clutched engagement with the engine shaft, see α on Fig. 3, when it is desired to transmit the engine power to the cable drum.

From the foregoing description taken in connection with the drawings, the general 75 arrangement and the manner of the use of my invention will be readily apparent.

The arrangement of the several parts that constitute my attachment is such that they may be readily applied to any of the usual 80 types of motor vehicles with practically no changes or alterations in the parts of the framing to which the attachment is to be applied.

In practice, one or both of the drums may 85 carry cables 9, having one end attached to the drum and the other end equipped with a claw hook 10 to provide for hooking onto a tree or stake, as indicated in Fig. 1 of the drawings, from which it is apparent that 90 should the vehicle get "stuck" from any of the usual causes, it is only necessary to hook the free end of the cable or cables around the stakes or trees, above the screw shaft into a clutched engagement with the 95 engine shaft and start the engine and thereby pull out the vehicle under its own power.

After the "auto" is pulled out, the "pull-out" is rendered inoperative by shifting the shaft 7 out of engagement with the engine 100 shaft.

What I claim is:—

1. In an automobile having a chassis frame and an engine provided with a crank shaft; a skeleton truss frame secured transversely to the chassis frame in front of the machine and having spaced front and back truss members, bearing brackets carried by 105

said truss frame and located between the front and back truss members, a drum carrying shaft journaled in said bearing brackets transversely of the machine, said truss frame having a top bearing structure, a worm shaft journaled in bearings in said top bearing structure, a worm gear on said drum shaft meshing with the worm of said worm shaft, and means to couple said worm shaft to the engine shaft at will.

2. In an automobile having a chassis frame and an engine provided with a crank shaft; a skeleton truss frame secured transversely to the chassis frame in front of the machine and having spaced front and back truss members, bearing brackets carried by said truss frame and located between the front and back truss members, a drum

carrying shaft journaled in said bearing brackets transversely of the machine, said truss frame having a top bearing structure, a worm shaft journaled in bearings in said top bearing structure, a worm gear on said drum shaft meshing with the worm of said worm shaft, and means to couple said worm shaft to the engine at will, said bearing structure comprising a body, a central opening and front and back bearing surfaces and a bearing cap also having front and back bearing surfaces, said worm shaft having bearing portions journaled in said bearing surfaces with the worm located in the open portion between the front and back bearing surfaces substantially as shown and described.

LOUIS HAMMER.
